MOTOR DRIVEN DISPENSER FOR PAPER TOWELING OR THE LIKE

Kenneth R. Bartleson, 824 W. 34th St.,
Baltimore, Md. 21211

Filed Oct. 4, 1965, Ser. No. 87,294

Term of patent 3½ years

(Cl. D52—2)

FIG. 1 is a perspective view of a motor driven dispenser for paper toweling or the like, showing my new design;

FIG. 2 is a front view thereof;

FIG. 3 is a side view thereof; and

FIG. 4 is a rear perspective view thereof showing the hinged lid in opened position.

I claim:

The ornamental design for a motor driven dispenser for paper toweling or the like, substantially as shown and described.
